A. W. SOUTHEY.
LIQUID FUEL BURNER.
FILED MAR. 14, 1922.

By Cushman, Bryant & Daffy
Atty.*

UNITED STATES PATENT OFFICE.

ALFRED WILLIAM SOUTHEY, OF LONDON, ENGLAND.

LIQUID-FUEL BURNER.

Application filed March 14, 1922. Serial No. 543,545.

To all whom it may concern:

Be it known that I, ALFRED WILLIAM SOUTHEY, a subject of the King of Great Britain and Ireland, residing at London, 5 England, have invented certain new and useful Improvements in Liquid-Fuel Burners, of which the following is a specification.

This invention relates to improvements in 10 burners for liquid hydrocarbon fuels, such, for example, as paraffin. The burner is one which is suitable particularly for use in cooking stoves, but is also suitable for other heating purposes, and also for lighting, if 15 used with an incandescing body.

One of the objects of the invention is to obtain a high temperature flame for heating purposes in a self contained apparatus working under natural draught.

20 Other objects of the invention are to obtain the utmost calorific value from the fuel and, what is particularly important for a burner used for cooking, to obtain a flame which will give no smell and with which no 25 free oil vapour is allowed to escape which might cause the food being cooked to smell or taste of oil.

According to the present invention there is complete combustion of a small portion 30 of the liquid fuel which is held in a wick, by means of which combustion another portion of the fuel in the wick is vapourized.

The vapour thus produced is very dense and liable to condense and in order to cause 35 it to mix easily with air for its complete combustion its density must be reduced.

The density of the vapour may be reduced by mixing a small portion of air with the vapour immediately it is generated when 40 it is at the highest temperature and this mixture of vapour and air can afterwards be mixed with additional air without condensation taking place.

The present invention accordingly consists 45 in providing a burner for liquid hydrocarbon fuel comprising a wick to which liquid fuel is supplied, confining the flame burning on said wick to a part only of the exposed portion of the wick, so as to reduce the volume of the products of combustion and so

that a further portion of the exposed wick is left from which, owing to the heat of the flame, dense liquid hydrocarbon vapour is given off, and providing means for diluting this vapour with air and for conveying the 55 mixture to a point where it can be ignited and burnt as a Bunsen flame.

The flame is preferably kept to the lower part of the exposed wick, and the admission of air just above the flame reduces the 60 draught acting on the flame and so helps to keep down the size of the flame and consequently the products of combustion.

The means provided for diluting the vapour are accordingly such as will not cause 65 the flame on the wick to spread unduly.

The invention further consists in conducting the mixture of vapour and air into the lower end of a tube to which additional air is admitted. This additional air may be admitted through openings at the lower end of the tube surrounding the opening through which the mixture enters the tube. 70

The invention further consists in the means described below for effecting these 75 objects.

The invention is illustrated in the accompanying drawing in which an improved burner suitable for use in a cooking stove is shown in sectional elevation. 80

1 is an ordinary oil container in which is suitably mounted a fixed sleeve 2. Within this sleeve there is arranged to slide a second sleeve 3 capable of being lowered and raised by means of an ordinary rack and pinion device 4 operated by a thumb disc. 85

The sleeve 3 contains the tubular wick 5 which fits closely within the sleeve and is adapted to rise and fall with it. Within the tubular wick 5 is slid a metal sleeve 6 90 which serves for keeping the tubular wick in position and shape and the wick with its internal sleeve 6 will be raised and lowered with the sleeve 3. The upper portion of the wick it will be seen extends above the sleeve 95 3 so that for part of its length the outside of the wick 5 is exposed.

Extending inwardly from the bottom of the sleeve 3 is an arm 7 on which is rigidly mounted a tube 8. Within this tube lies a 100

spindle 9 which carries near its upper end a horizontal disc 10 which when the burner is assembled rests upon the top of the tubular wick 5. The upper end of the spindle 5 is threaded and on to it is screwed the boss 11 of a three-armed spider 12 which carries the upper portion of the burner. This consists of a Bunsen tube 13 across the upper end of which is fixed a perforated metal 10 plate or plates 14. The perforated plate 14 is preferably made in known manner of three layers of metal with the perforations coinciding, this construction serving to ensure that the heat of the flame which is 15 lighted above the plate 14 will not raise the temperature of the plate to such an extent that the flame will light back into the tube 13.

On the lower end of the tube 13 is carried 20 the flame restricting means 15 which in the construction illustrated is in the form of a truncated conical body of metal open at its lower end and having perforations 18 near its narrow end. This conical body is carried upon the lower end of the tube 13 by means of a perforated metal part comprising a perforated cylindrical portion 16 and a perforated annular portion 17 fixed to the tube 13, and forming an internal flange. 25

30 The tube 13 with the attached parts 15, 16, 17, 9 and 10 may be removed from the remainder of the burner and to facilitate replacement the upper portion of the tube 8 is fitted with a funnel shaped mouth 8'. 35 For extinguishing the flame a cap 19 may be provided which fits over the upper end of the tube 13.

The operation of the burner is as follows:—The tube 13 and the attached parts 40 are removed by hand (or they may be raised a sufficient distance by raising the sleeve 3 and the wick within it), so that the upper portion of the wick can be lit. Upon the 45 upper portion of the burner being replaced, so that the disc 10 rests upon the top of the wick (or upon the sleeve 3 being lowered) it will be found that the flame is confined to a narrow zone on the exposed portion of the wick just above the edge of the 50 sleeve 3, air rising by natural draught under the open end of the conical body 15, to keep the flame alight. The flame will burn blue round the lower portion of the exposed wick and the heat therefrom causes a dense vapour to rise from the upper exposed portion of the wick. Air enters by the perforations 18 at the top of the conical body 15 and also through the perforations in the cylindrical part 16 and mixes with the hot 55 vapour, so that a mixture of oil vapour, air and the gases of combustion from the flame below rise through the restricted passage 60 between the cylindrical part 16 and the outside of the wick 5 and pass into the lower

end of the tube 13. The perforated conical bodies 15 and 16 provide for the dilution of the vapour, without allowing the flame on the wick to spread unduly.

Further air is admitted through the perforations in the annular disc 17 and the mixture rising from the wick expands and mixes with this additional air and rises in the tube 13 and can be lit and will burn with a clear blue flame above the perforated plate 14.

When the lamp is to be extinguished it is desirable to lower the sleeve 3 containing the wick 5 by means of the rack and pinion 4 and when the flame is almost extinguished by this operation the cap 19 may be placed 80 upon the upper end of the tube 13.

The flame produced above the upper end of the tube 13 is an intensely hot flame and burns entirely free from smell and no vapour of oil rises with it, so that the upper 85 end of the burner may be placed below an opening in the bottom of an oven, for example, and the flame may enter the oven space and food may be cooked by the heat within the oven without acquiring any taste 90 or smell from the oil.

Having thus described my invention, what I claim and desire to protect by Letters Patent is:

1. In a liquid hydrocarbon burner, the 95 combination of a wick, means supporting the wick and exposing a section thereof on which the liquid fuel can be ignited, means for supplying air to the exposed section of the wick in sufficient quantity to support a flame on 100 a portion only of said exposed section, the heat of such flame effecting vaporization of the liquid fuel in the remainder of the exposed section of the wick, and a mixing 105 chamber receiving said vapor and having a burner outlet.

2. In a liquid hydrocarbon burner, the combination of a wick, means supporting the wick and exposing a section thereof on which the liquid fuel can be ignited, means surrounding the exposed section of the wick and restricting the admission of air thereto so that the flame of ignited fuel will be confined to a portion only of the exposed 115 section of the wick, the heat of such flame effecting vaporization of the liquid fuel in the exposed section of the wick outside of the flame area, a mixing chamber positioned to receive said vapor and having a burner outlet, and means for supplying air to said chamber.

3. In a liquid hydrocarbon burner, the combination of a wick, means supporting the wick and exposing a section thereof on which the liquid fuel can be ignited, means 125 permitting access of air to the exposed section of the wick sufficiently to support a flame in the lower portion only of said sec-

tion when the liquid fuel is ignited, the heat of such flame effecting vaporization of the liquid fuel in the exposed section of the wick above the flame area, and a mixing chamber receiving said vapor and having a burner outlet.

4. In a liquid hydrocarbon burner, the combination of a wick, means supporting the wick and exposing a section thereof on which the liquid fuel can be ignited, means adapted to confine the flame of the ignited fuel to a portion only of the exposed wick section, means adapted to supply air in restricted amount to the portion of the exposed section of the wick where there is no flame, a mixing chamber arranged to receive said air and vapor generated in the exposed section of the wick by the flame and provided with a burner outlet, and means for supplying additional air to said chamber.

5. In a liquid hydrocarbon burner, the combination of a wick, means supporting the wick and exposing a section thereof on which the liquid fuel can be ignited, means adapted to confine the flame of the ignited fuel to a portion only of the exposed wick section, means adapted to supply air in restricted amount to the portion of the exposed section of the wick where there is no flame, a mixing chamber arranged to receive said air and vapor generated in the exposed section of the wick by the flame and provided with a burner outlet at its upper end, and means for supplying additional air to the lower end of the mixing chamber.

6. In a liquid hydrocarbon burner, the combination of a wick, means supporting the wick and exposing a section thereof on which the liquid fuel can be ignited, means adapted to confine the flame of the ignited fuel to a portion only of the exposed wick section, means adapted to supply air in restricted amount to the portion of the exposed section of the wick above the flame area, and a mixing chamber arranged to receive said air, products of combustion from the flame and vapor generated by the heat of the flame on the wick outside of the flame area, said chamber having a burner outlet.

7. In a burner for liquid hydrocarbons, a wick upon an exposed portion of which the liquid fuel can be ignited, means adapted to confine the flame of the ignited fuel to the lower portion only of the exposed wick, means adapted to admit air in restricted quantity to the portion of the exposed wick above the flame and a mixing chamber into which the mixed vapour and air are drawn and at the top of which the mixture is burnt.

8. In a burner for liquid hydrocarbons, a wick, a screen surrounding said wick, and under the lower edge of which air can pass to the wick and through part of which further air can pass to the wick, said screen

being of such size as to leave only a restricted passage between it and the wick, and a mixing chamber above said wick and screen.

9. In a burner for liquid hydrocarbons, a wick, a screen having a conical portion surrounding said wick, under the lower edge of which air can pass to the wick and through part of which further air can pass to the wick, said screen being of such size as to leave only a restricted passage between it and the wick, and a mixing chamber above said wick and screen.

10. In a burner for liquid hydrocarbons, a wick, a screen surrounding said wick, and under the lower edge of which air can pass to the wick and a cylindrical portion through which further air can pass to the wick, said screen being of such size as to leave only a restricted passage between it and the wick, and a mixing chamber above said wick and screen.

11. In a burner for liquid hydrocarbons, a wick, means surrounding said wick and adapted to allow access of air to one portion of the wick to a sufficient degree to support combustion and to another portion of the wick to an insufficient degree to support combustion, a mixing chamber above said wick having apertures at the lower end through which the air has access to the interior of the mixing chamber.

12. In a burner for liquid hydrocarbons, the combination of a liquid receptacle, a vertically adjustable wick tube connected to the receptacle, a wick extending throughout the length of and projecting above and below the wick tube, a tube supported above the wick and provided with a burner outlet, and a screen depending from the last said tube and surrounding the exposed portion of the wick above the wick tube, said screen having a perforated section adjacent its upper end, for the purpose described.

13. In a burner for liquid hydrocarbons, the combination of a liquid receptacle, a vertically adjustable wick tube connected to the receptacle, a wick carried by the wick tube and extending beyond the upper end thereof, a mixing chamber supported at the upper end of the wick and provided with a burner outlet, said chamber having a series of air inlets at its lower end, and means surrounding the portion of the wick above the wick tube for limiting the flame produced by lighting fluid on the exposed portion of the wick to the lower section of such exposed section and conducting vapor generated in the upper section of the exposed portion of the wick by said flame to the mixing chamber.

14. In a burner for liquid hydrocarbons, the combination of a liquid receptacle, a vertically adjustable wick tube connected to the receptacle, a wick carried by the wick tube

and extending beyond the upper end thereof, a tube within the wick and extending to the upper end thereof, a mixing chamber supported on the upper end of the inner wick
5 tube and provided with a burner outlet, said chamber being provided with air inlets at its lower end, and a screen connected with the mixing chamber and depending therefrom about the portion of the wick that ex-
10 tends above the outer wick tube, said screen

having a perforated section adjacent its upper end and forming about the wick a passage leading to the mixing chamber, for the purpose described.

In witness whereof, I have hereunto set 15
my hand this 28th day of February 1922.

ALFRED WILLIAM SOUTHEY.
